United States Patent

Des. 240,535
Patented July 13, 1976

240,535

FLOOR TOILET OR THE LIKE

Earl L. Morris, Whittier, Calif., assignor to Acorn
Engineering, City of Industry, Calif.

Filed Mar. 10, 1975, Ser. No. 557,022

Term of patent 14 years

Int. Cl. D23—02

U.S. Cl. D23—67

Fig. 1.

Fig. 3.

Fig. 2.

Fig. 4.

Fig. 5.

Fig. 6.

FIG. 1 is a top plan view of a floor toilet or the like showing my new design;

FIG. 2 is a side elevational view thereof;

FIG. 3 is an elevational view taken from the right end thereof;

FIG. 4 is an elevational view taken from the left end thereof;

FIG. 5 is a cross sectional view taken on line 5—5 of FIG. 1; and

FIG. 6 is a cross sectional view taken on line 6—6 of FIG. 2.

I claim:

The ornamental design for a floor toilet or the like, as shown.
